UNITED STATES PATENT OFFICE.

GEORGE BENNET, OF HELENA, MONTANA TERRITORY.

IMPROVEMENT IN LINIMENTS.

Specification forming part of Letters Patent No. 177,790, dated May 23, 1876; application filed April 7, 1876.

To all whom it may concern:

Be it known that I, GEORGE BENNET, of Helena, in the county of Lewis and Clarke, in the Territory of Montana, have discovered a new composition of matter, being a Liniment for Rheumatism, of which the following is a written description sufficient to enable others skilled in the science to which it relates to compound and use the same.

This invention relates to the well-known class of liniments; and it consists of the compound herein set forth.

To prepare the liniment I take, of croton-oil, two drams; of tincture of iodine, four ounces; of oil of origanum, four ounces; of tincture of Spanish flies, four ounces, and of the spirits of turpentine, one pint. Mix well, and the liniment is ready for use.

This liniment is useful in all kinds of rheumatism. Its effect is to subdue the soreness, pain, and inflammation, and, consequently, to reduce swellings. Only ordinary care is re-

quired in applying it to the skin. It should not be applied too often or too lavishly. As in the use of all other liniments, balsams, and the like, the feelings of the patient and the common sense of the nurse indicate the quantity and frequency of the application. The filled hollow of an open hand, well rubbed in, should be ample. After its application several times, the skin will become covered with small pimples, the soreness and pain ceases, and the pimples soon disappear.

I claim—

A compound of croton-oil, iodine, oil of origanum, Spanish flies, and spirits of turpentine, forming a liniment for rheumatism.

In testimony whereof I have affixed my signature in the presence of two witnesses.

GEORGE BENNET.

Witnesses:

A. E. H. JOHNSON,

J. W. HAMILTON JOHNSON.
